US0D1073440S

(12) **United States Design Patent** (10) **Patent No.:** **US D1,073,440 S**
(45) **Date of Patent:** **** May 6, 2025**

(54) **CONTAINER MAGNETIC DEVICE MOUNT**

(71) Applicant: **Scosche Industries, Inc.**, Oxnard, CA (US)

(72) Inventors: **Kasidy Alves**, Oxnard, CA (US); **Vince Alves**, Oxnard, CA (US); **Yasuhiro Yamamoto**, Thousand Oaks, CA (US)

(73) Assignee: **Scosche Industries, Inc.**, Oxnard, CA (US)

(**) Term: **15 Years**

(21) Appl. No.: **29/877,669**

(22) Filed: **Jun. 9, 2023**

(51) LOC (15) Cl. **08-08**

(52) U.S. Cl.

USPC **D8/349**; D14/253

(58) **Field of Classification Search**

USPC D8/354, 355, 356, 363, 364, 366, 367, D8/368, 370, 371, 373, 380, 382, 385, D8/394; D14/253

CPC A47G 19/2272; A47G 19/2227; B65D 43/02; B65D 1/0207

(57) **CLAIM**

The ornamental design for a container magnetic device mount as shown and described.

DESCRIPTION

FIG. 1 is a rear perspective view showing a container magnetic device mount in an environment of use;

FIG. 2 is a front perspective view thereof;

FIG. 3 is a top view thereof;

FIG. 4 is a right side view thereof;

FIG. 5 is a left side view thereof;

FIG. 6 is a front view thereof;

FIG. 7 is rear view thereof; and,

FIG. 8 is a bottom view thereof.

In the drawings, the broken line showings are for purposes of illustrating portions of a container magnetic device mount and environment. All broken lines form no part of the claimed design.

1 Claim, 4 Drawing Sheets
